UNITED STATES PATENT OFFICE

IRVING C. HOWES, OF NORTH ANDOVER, MASSACHUSETTS, ASSIGNOR TO DAVIS & FURBER MACHINE COMPANY, OF NORTH ANDOVER, MASSACHUSETTS, A CORPORATION OF MASSACHUSETTS

JOURNAL-BEARING CONSTRUCTION

Application filed September 12, 1926. Serial No. 135,067.

This invention relates to a journal bearing construction wherein a journal bearing sleeve having a lubricant-holding recess communicating with the bearing surface is employed, and the object of the invention is to provide means for positioning the bearing sleeve with the lubricant-holding recess at the top independently of the angular position of the bearing block in which the sleeve is mounted.

10 The invention is particularly designed for use in a carding machine in connection with the bearings for the worker and stripper rolls, the bearing blocks for which are necessarily mounted in various angular positions around the arch of the frame.

15 The objects and features of the invention will appear more fully from the accompanying description and drawings and will be particularly pointed out in the claims.

20 While the invention is applicable to various bearing constructions in various machines, it is particularly useful in connection with a carding machine and a simple and preferred form of construction embodying the invention is here illustrated in connection with such a machine.

In the drawings:

Fig. 1 is a side elevation of a portion of the arch of the frame of a carding machine with one unit of a worker and stripper roll in one angular position thereon.

Fig. 2 is a detail partially in end elevation and partially in section of a portion of the bearing for the stripper roll shown in Fig. 1.

35 Fig. 3 is a view partially in transverse section on the line 3—3 of Fig. 2.

In the particular construction illustrated, a portion of the arch 1 of the frame of a carding machine is shown. Such an arch is 40 usually formed on a circular arc and a plurality of units, each comprising a worker roll and a stripper roll, which are located in different angular positions, that is, on different radii of the arch, usually throughout substantially 180°.

In the construction illustrated, a single unit is shown in one angular position. This unit comprises a base plate 2 secured at the required angular position to the arch and on 50 this base plate is adjustably mounted a bear-

ing block 3 for the worker roll 4 and a bearing block 5 for the stripper roll 6. It will thus be seen that these bearing blocks may occupy any angular position, or any position radially of the arch, from the vertical to substantially the horizontal and in the illustrated position are shown between these two extreme positions.

The bearing construction in the case of both worker roll and the stripper roll is the same so that it is only necessary to illustrate and describe in detail but one, and for that purpose the bearing construction of the stripper roll is taken.

It will be understood, of course, that the construction may be and is preferably the same at each end of the worker and stripper rolls.

The stripper roll 6 is provided at each end with a journal 7. On this journal is mounted a journal bearing sleeve 8. This sleeve is provided on the top or upper side with a lubricant holding recess 9, herein shown as a shallow cup formed in the metal of the sleeve and adapted to receive a supply of oil, grease or other lubricant. This recess, by means of suitable apertures 10 extending from its bottom through the sleeve, communicates with the bearing surface and serves to lubricate the journal 7.

It will be seen, therefore, that it is necessary that this lubricant-holding recess 9 shall always be located at the top quite independently of the angular position of the bearing block on the frame of the machine and it is the principal object of the invention to secure this result.

The bearing block 5 is provided at its upper end with a curved seat, preferably semi-circular, and preferably presenting an open mouth. In the particular construction illustrated, this seat presents the opposed frusto-conical surfaces 11 and the intermediate surface 12.

The sleeve is preferably formed with an annular flange presenting opposed frusto-conical surfaces 13 cooperating with the surfaces 11 and with an intermediate flat surface 14 between.

A plurality of circumferentially spaced re-

cesses and a cooperating projection are located, the one at the exterior surface of the sleeve and the other at the surface of the bearing block seat. In the form illustrated, the 5 projection 15 extends from the interior surface 12 of the bearing block seat and the cooperating plurality of recesses 16 are formed in the flat surface 14 of the sleeve. The cooperating elements comprising the recesses on 10 the one hand and the projection on the other present cooperating positioning means on the sleeve and bearing block and the relative location of these elements may be as desired, although preferably the projection is on the 15 bearing seat and the recesses on the journal bearing sleeve as illustrated.

It will thus be seen that when the bearing sleeve is inserted in the bearing seat, preferably by being inserted transversely through 20 the open mouth of the bearing seat in the construction illustrated, that one or the other of the recesses 16 may be brought into cooperation with the projection 15 so as position the lubricant-holding recess 9 at the top, no 25 matter what may be the angular position of the bearing block itself. When the journal bearing sleeve has thus been placed in position, it is thus held, usually by gravity, in its adjusted position with the lubricant-holding 30 recess at the top, and thus there is no danger of the lubricant spilling or working out from the recess whatever may be the angular position of the bearing block.

Having thus described the invention, what 35 is claimed as new, and desired to be secured by Letters Patent, is:

1. A journal bearing construction comprising a journal bearing sleeve having a lubricant holding recess communicating with the bearing surface, a bearing block having a 40 curved seat cooperating with the exterior surface of the sleeve and supporting the sleeve, and a plurality of circumferentially spaced recesses and a cooperating projection 45 located the one at the exterior surface of the sleeve and the other at the surface of the bearing seat whereby the sleeve may be positioned and held in the seat with the lubricant recess at the top independently of the angular 50 position of the bearing block.

2. A journal bearing construction comprising a journal bearing sleeve having a lubricant holding recess communicating with the bearing surface, a bearing block having a 55 curved seat cooperating with the exterior surface of the sleeve and supporting the sleeve, and a plurality of circumferentially spaced recesses in the exterior surface of the sleeve and a cooperating projection on the bearing 60 block seat whereby the sleeve may be positioned and held in the seat with the lubricant recess at the top independently of the angular position of the bearing block.

3. A journal bearing construction comprising a journal bearing sleeve having a lubri-

cant holding recess communicating with the bearing surface, a bearing block having a semi-circular open mouth seat into which the sleeve is inserted through the mouth and cooperating positioning means on the sleeve and bearing block acting to hold the sleeve, when seated, with the lubricant recess at the top independently of the angular position of the bearing block.

4. A journal bearing construction comprising a journal bearing sleeve having a lubricant holding recess communicating with the bearing surface, a bearing block having a curved seat cooperating with the exterior surface of the sleeve and supporting the sleeve, and cooperating positioning means on the sleeve and bearing block acting to hold the sleeve, when seated, with the lubricant recess at the top independently of the angular position of the bearing block.

In testimony whereof, I have signed my name to this specification.

IRVING C. HOWES.
